United States Patent Office.

DEXTER CURTIS, OF CHICAGO, ILLINOIS.

Letters Patent No. 105,917, dated August 2, 1870.

IMPROVED HORSE-COLLAR CAP.

The Schedule referred to in these Letters Patent and making part of the same.

To all whom it may concern:

Be it known that I, DEXTER CURTIS, of Chicago, in the county of Cook and State of Illinois, have invented a new and useful Horse-collar Cap; and I do hereby declare the following to be a full, clear, and exact description thereof, which will enable others skilled in the art to which my invention appertains to make and use the same, reference being had to the accompanying drawing forming part of this specification.

Figure 1 is a perspective view of my improved horse-collar cap, and

Figure 2 is a longitudinal section of the same.

Similar letters of reference indicate corresponding parts in the several figures of the drawing.

My invention has for its object to protect the neck of a horse from injury by the horse-collar, and

To this end it consists in two curved plates of metal, secured one upon the other, with an air-passage between them, the under plate being composed of zinc and the upper plate of iron, copper, or other suitable metal.

Horse-collar caps have heretofore been constructed of a curved metal top plate and a leather strip secured to the under side of the same, in such a manner as to leave an air-passage between them.

When the leather becomes moistened by contact with the neck, it stretches to such an extent under the weight of the collar as to close the air-passage and prevent the escape of moisture.

The leather, therefore, becoming continually moist, is liable to chafe the neck, rather than prevent such injury.

By constructing the lower plate of zinc, as I propose, it can neither yield, under the weight of the collar, to close the air-passage, nor become sticky and abraded to chafe the neck.

In connection with this mechanical action, by which

the lower plate is kept cool and the neck prevented from chafing, the zinc possesses medicinal qualities, by which old sores or wounds are speedily healed.

In the accompanying drawing—

A is a plate, composed of iron, copper, or other suitable metal, bent in the arc of a circle, as shown, and secured firmly at its side edges to a second curved plate, B, composed of zinc, in such a manner as to leave a space, C, between them, for the circulation of air.

The zinc plate is extended somewhat beyond the ends and sides of the upper plate, and bent up slightly, to rest firmly upon the horse's neck without cutting or galling the same.

The cap is applied by being placed upon the neck of a horse, and the two ends of the collar buckled together over the plate A.

For the purpose of securing the collar firmly to the cap, the plate A is provided upon its upper surface with a longitudinal strap, D, of leather or metal, so connected to said plate as to form two or more loops, E, through which the straps upon the ends of the collar pass.

My improved cap not only prevents the horse's neck from chafing, but possesses healing properties by which wounds and sores are readily cured.

Having thus described my invention,

What I claim as new, and desire to secure by Letters Patent, is—

The horse-collar cap, consisting of the curved plates A B, secured together in such a manner as to leave an air-passage between them, the former being composed of any suitable metal, and the latter of zinc, substantially as described, for the purpose specified.

DEXTER CURTIS.
